GAS PURIFICATION

Harry L. Gilmore, Adrian, Mich., assignor to
 Aget Manufacturing Company, Adrian, Mich.,
 a corporation of Michigan

Application September 21, 1942, Serial No. 459,140

2 Claims. (Cl. 183—45)

This invention relates to the handling of gas to and through a filter, especially at volume rate.

This invention has utility when incorporated in multi-stage removal of particles from a fluid by cyclone and filter, and the installation unit therefor.

Referring to the drawings:

Fig. 1 is an elevation of the air purifier unit embodiment of the invention, with the housing below the filter removed, and looking at the motor end of the motor-blower therefor;

Fig. 2 is a view at right angles to the showing in Fig. 1, portions being broken away;

Fig. 3 is a detail view of the upper head section for the filter;

Fig. 4 is a section on the line IV—IV, Fig. 1, through the filter, and showing the cyclone tangential draft receiver;

Fig. 5 is a partial section on the line V—V, Fig. 2, showing the uptake from the blower, and a fragment of the coarse particle receiver jar;

Fig. 6 is a section on the line VI—VI, Fig. 1, showing the deflectors near the port terminus of the discharge leg for the cyclone dust collector;

Fig. 7 is a view from the line VII—VII, Fig. 5 showing the intake tube section or thimble to the fan or blower;

Fig. 8 is a section on the line VIII—VIII, Fig. 7, showing the integral structure of the port and throat;

Fig. 9 is a view similar to Fig. 8, wherein, instead of a port directly extending outwardly from the throat, there is provided a dome adaptable for multiple intake connection;

Fig. 10 is a section, with parts broken away, through the double wall for the filter with the filler fiber in place before the heads are applied thereto; and

Fig. 11 is a view similar to Fig. 10, with the heads assembled with the fiber excess effecting sealing therewith.

The turning on of electric switch 1 starts motor 2 having shaft 3 upon which is mounted multi-blade fan 4. There is thus provided a direct-connected motor-blower unit. Normally enclosing this motor-blower unit and rising upwardly therefrom is housing 5. Axially of the fan the housing 5 has opening 6 which has thereabout flat ring or flange 7 anchored with the housing 5 by self tapping screws 8 radially inward from bounding bead 9. Extending into the opening 6 is throat 10 (Fig. 8). For single intake, there may be restriction 11 therefrom to intake duct or port 12 adapted to have connection 13 say to hood 14 (Fig. 2) from an abrading or polishing

wheel 15. The particle laden air as drawn through the intake 12 is so directed by the throat 12 that in normal fan operation there is no tendency to eddy about the ends of the blades of the fan 4.

In instances where it is desired to connect more than one region for having air exhausted therefrom, there is installed, in lieu of the single inlet unit (Fig. 8), a dome 16 with a desired number 10 of ports 17 for connecting ducts 18. Bead 9 may be omitted from the flange 7 of the throat 10, and flange 19 anchored thereupon by screws 8. Peripheral stiffening bead 20 also serves as a trim for this intake throat fitting (Fig. 9).

15 Registering with this opening 6 in the housing 5 is fan housing side 21 with its opening 22. The side 21 in this assembly is adapted for placement directly against the housing 5, and has marginal flange 22' extending away from the housing 5. About this flange 22' may be placed scroll body 23 with weld anchoring on the inside. Companion fan housing side 24 adjacent the motor has central opening 25 for the motor shaft 3. The margin of the side 24 carries a flange 26 similar to the flange 22' of the side 21, but extending toward the motor 2, or away from the fan 4 (Figs. 2, 5). There is thus provided a scroll housing about the fan 4 with rectangular cross-section riser 27 near a corner leg 28 rising from base 29, and about which extends the housing 5. The riser 27 extends to elbow 30 with tangential discharge 31 to intake port 32 at cylindrical receiving portion 33 of a cyclone type dust collector (Fig. 4).

30 35 The cyclone dust collector from its cylindrical receiving chamber 33 has the clockwise swirl as coarser or heavier portions progress downwardly along the tapering section 34 toward discharge port 35 having screw section 36, say similar to a fruit-jar top, adapted for thread connection with throat 37 of glass type fruit jar 38 as a coarser particle receiver. The accumulation of particles may thus be readily observed and timely attention given for emptying or replacing this receiver.

40 45 In order to dissipate the travel rate and thereby contribute to early quiet repose of these particles, the section 34 near the port 35 has one or more wings or vanes 39 (Fig. 6). The vanes 39 are arched or dished to form a side 40 with the vane 50 extending toward the port in the clockwise direction of the swirl. The particles pass into the jar or receiver 38.

45 50 The incoming gas to the cyclone dust collector, although more or less purified gas, and at reduced velocity, may eddy upward through con-

centric exhaust 41 (Fig. 4) into chamber 42 of the filter.

Foraminous sheet 43, say of expanded metal, may be welded at 44 into a cylinder, about which may be wrapped filter fiber 45, say of fiber glass, which may be as light as 3½ lbs. per cubic foot. Inasmuch as the normal placing of the filter is with its axis vertical, the inner wall of the double wall structure has a lower but slight outward offset 46, while there is at the upper end a larger crowding section or flange 47. The loose fiber 45 of generally uniform and homogeneous character in its initial wrapping about the inner wall foraminous tube 43, has excess 48 (Fig. 10) terminally thereof. Outer foraminous wall 49 may 15 be of similar expanded metal to the inner wall 43. Tongues 50 overlap between the ends of the wall 49 to hold the wall 49 to embrace the filler 45 with terminal minor inturned edges 46, the lower being toward the edge 46 of the wall 43, while the upper is toward the major and rather stiff flange 47.

Assembly of heads with this double side wall fiber filled foraminous tube produces the filter of volume for rapidly passing air in considerable quantity, uniformly treated for elimination of particles therefrom. Lower head 51 (Fig. 11) has bounding flange 52 with holding means or anchorage 53 for concentric inner flange 54. Upper head 55 has outer flange 56 with seat 57 therefrom to opposing wedge or seat portion 58. The flanges 52, 56, are toward each other and of common diameter. The flange 54 is toward the wedge 58. Bolts 59 extending through the heads 55, 51 with wing nuts 60 thereon, permit crowding down of the excess 48 of the fiber 45 in providing automatic gasket assembly of the heads in the filter. The more rigid wedge 58 so acts upon the crowding section or flange 47 that there is such holding of the loose fiber at the upper terminus of this vertical axis double-wall filter that in practice, notwithstanding slight vibrations, say as arising from the blower or other machine operations, long continued service has not developed any sagging or any departure from uniformity of fiber, effective filtering, or screening maintenance as installed. While this double foraminous wall fiber filled filter may be directly connected to take exhaust from a blower or other entrained gas or air supply, a quite advantageous capacity increase is had in the stage removal through the interposition of the cyclone. Exceptional practical values arise from such multi-stage particle removal assembly unit, for the

coarse fragments are conveniently taken as found accumulated, from the jar 38. The filter fiber 45, as of fiber glass, does not deteriorate physically and in normal operations approaches a permanent set up. When it is found there is detrimental lag in air or gas passage through the filter, cleansing may then be had of the filler or fiber 43 in or out of the double wall structure. However, replacement with new fiber directly 10 restores to initial efficiency.

In placing the flange 54 (Fig. 11), with its outwardly extending flange against the head 51, it is held by anchorage 53 along the flange flat portion.

Compactness in the cyclone and filter assembly is adopted in having the cylindrical chamber 33 of the cyclone extend up into the filter chamber 42. The distance of this extent is desirably such that the exhaust opening 41 is not restricted by proximity to the head 55. This means that the cross-sectional extent or area of the exhaust 41 is not in excess of the cylindrical spill area over the upper terminus of the cyclone into the filter chamber 42. The exhaust from the cyclone dust collector thus has expansion and course or direction change as entering the chamber 42, thereby promoting further release of particles to fall on the lower head 51. This action reduces the entraining quantity of particles in the filter and further contributes to maintenance of uniform operation over an extended time period.

What is claimed and it is desired to secure by Letters Patent is:

1. A cylindrical filter comprising a perforate 35 inner tubular wall and an outer perforate tubular wall forming a shell, a homogeneous fiber filler between said walls, said inner wall having integral outwardly offset portions at opposite ends thereof embedded in said filler in a manner to 40 compress a portion of said filler between said offset portions and said shell to support the same and prevent settling thereof.

2. A cylindrical filter comprising a perforate shell of a pair of radially spaced inner and outer 45 walls, one of said walls at an end thereof having offset portions extending toward the other wall, and a homogeneous fiber filler in the shell into which said offset portions are embedded in a manner to compress a portion of said filler between 50 said offset portions and said shell to retain the filler against shifting in the shell away from engagement by the offset portions.

HARRY L. GILMORE.
